JOHN HAYS HAMMOND, JR., OF GLOUCESTER, MASSACHUSETTS.

LAUNCHING MECHANISM FOR TORPEDOES.

1,418,795.

Specification of Letters Patent. Patented June 6, 1922.

Application filed January 12, 1916, Serial No. 71,710. Renewed March 14, 1918. Serial No. 222,515.

To all whom it may concern:

Be it known that I, JOHN HAYS HAMMOND, Jr., a citizen of the United States, and a resident of Gloucester, in the county 5 of Essex and State of Massachusetts, have invented certain new and useful Improvements in Launching Mechanism for Torpedoes, of which the following is a specification.

10 One of the objects of this invention is to provide improved launching mechanism particularly adapted to be used in launching a torpedo from a torpedo boat, and arranged to reduce the speed of the torpedo boat automatically and at such a time as to insure an effective launching of the torpedo, and operative to return the boat to its initial speed in a predetermined time after the launching has been effected.

20 Other objects of this invention will appear hereinafter.

In the accompanying drawings, Fig. 1 is a diagrammatic plan view of a torpedo boat provided with torpedo launching mechanism constructed in accordance with this invention; and Figs. 2 to 6 are diagrammatic plan views of modified forms of this invention.

Referring to Fig. 1 of the drawings, one 30 embodiment of this invention comprises a torpedo boat provided with a cylindrical torpedo tube 5 fixedly secured therein and arranged to contain a torpedo 6 and to permit the same to be launched longitudinally 35 through the open end of the tube and into the surrounding water. In the form of the invention shown in Fig. 1, the torpedo tube 5 is arranged longitudinally of the torpedo boat to launch a torpedo forwardly from the bow of the boat and in the direction of the motion of the boat but the torpedo tube 40 might be arranged in any other desired relation to the boat.

For supplying compressed air to the 45 inner end of the torpedo tube 5 to eject the torpedo 6 from the tube, the inner end of the torpedo tube 5 is connected by a pipe 7 with a pipe 8 which leads from a tank 9 or other source of compressed air upon the 50 boat, the pipe 7 being controlled by a manually adjustable valve 10, and also by a reciprocating slide valve 11 which is provided with a port 11', and is rigid with one end of a plunger 12 which forms the core of a 55 fixed solenoid 13. A spiral spring 14 sur-

rounds the plunger 12 and is compressed between solenoid 13 and a collar 15 rigid with the plunger, and normally holds the slide valve 11 in such a position as to prevent the air from flowing through the inlet 60 pipe 7 and into the torpedo tube 5.

For propelling the torpedo boat through the water, the boat is provided in the form shown with a pair of propellers 16 and 17 which have swiveling or reversible propeller blades 18 and 19 of any well known or suitable construction. These propellers 16 and 17 are mounted upon and arranged to be driven by two parallel shafts 20 and 21 arranged to rotate about their longitudinal 65 axes in suitable bearings and to be rotated by internal combustion engines or any suitable engines or actuating means (not shown).

The two propellers 16 and 17 are operatively connected respectively to two sleeves 22 and 23 which are arranged to reciprocate in the corresponding shafts 20 and 21 to swing the corresponding propeller blades 18 and 19 about axes extending 70 transversely of the shafts 20 and 21 respectively to vary the pitch of these blades, and to reverse the pitch when the sleeves 22 and 23 are moved through sufficient distances. For reciprocating the sleeves 22 and 23, two 75 levers 25 and 26 are arranged to oscillate about fixed pivots 27 and 28 respectively, and are provided with pins 30 and 31 rigid therewith respectively which engage loosely in annular recesses 32 and 33 provided 80 therefor in the sleeves 22 and 23. The free ends of the levers 25 and 26 are provided with longitudinal slots 35 and 36 in which slidably engages a pin 37 rigid with one end of a piston rod 38 the other end of 85 which is provided with a piston 39 arranged to reciprocate in a fixed cylinder 40. This cylinder 40 is provided with a port 41 arranged to communicate through an inlet pipe 42 with the pipe 8 leading from the 100 source of compressed air 9, the inlet pipe 42 being controlled by a manually adjustable valve 43. The port 41 is also arranged to communicate with an outlet pipe 45 which is controlled by a manually adjustable 105 needle or globe valve 46. A reciprocating slide valve 47 having an inlet port 48 and an outlet port 49 is arranged to connect the port 41 alternately with the inlet pipe 42 and with the outlet pipe 45, and this slide 110

valve 47 is rigid with a plunger 50 which forms the core of a fixed solenoid 51. A spiral spring 52 surrounds the plunger 50 and is compressed between the solenoid 51 and a collar 53 rigid with the plunger 50 and normally holds the slide valve in such a position as to prevent air from passing into the inner end of the cylinder from the inlet pipe 42, and to permit the inner end 10 of the cylinder to communicate through the outlet port 49 with the outlet pipe 45. A compressed spiral spring 54 within the cylinder 40 normally holds the piston 39 in its innermost position which causes the propeller blades 18 and 19 to be held at such a pitch that when they are rotated they will give the torpedo boat a maximum speed forward.

For reducing the speed of the torpedo boat, and ejecting the torpedo 6 from the tube 5, any suitable means may be provided for controlling the propellers 16 and 17, and the inlet of air into the torpedo tube 5, but in the form of the invention shown in 25 Fig. 1 there is provided means for successively reducing the speed of the torpedo boat and ejecting the torpedo, and in the form shown, this means includes a battery or other source of electrical energy 60, one 30 pole of which is connected by a coiled wire 61 with a movable contact 62, and the other pole of which is connected by a wire 63 with one end of the solenoid 13. The other end of the solenoid 13 is connected by a wire 35 64 with a stationary contact 65 arranged in the path of the movable contact 62.

The movable contact 62 is carried by the inner end of a plunger 66 which reciprocates through a cylinder 67. A piston 68 fits snugly within the cylinder 67, and is rigidly secured to the plunger 66, and the plunger 66 is normally held in an inoperative position by a compressed spiral spring 69 arranged within the cylinder 67. The 45 outer end of the cylinder 67 communicates with the surrounding air through a pipe 70 controlled by an inwardly opening check valve 71 and provided with a by-pass 72 controlled by an adjustable needle or globe 50 valve 73, the construction and arrangement being such that the check valve closes automatically when the piston 68 moves outwardly and the air is allowed to pass out of the cylinder only through the by-pass 72, 55 thus retarding the outward movement of the piston 68, but when the piston moves inwardly under the action of the spring 69 the check valve 71 opens automatically and permits the air to enter freely into the cylinder 60 to expedite the inward movement of the piston 68. The inner end of the cylinder 67 is provided with open ports 74 to permit the air to pass freely into and out of the inner end of the cylinder.

65 The outer end of the plunger 66 forms

the core of a fixed solenoid 75, one end of which is connected by a wire 76 to one pole of a battery 77, the other pole of which is connected by a wire 78 with a normally open switch 79, which is arranged to be moved into and out of engagement with a stationary contact 80, which is connected by a wire 81 with the other end of the solenoid 75. The switch 79 is normally held open by a spiral spring 82, and is arranged to be closed in any suitable manner or by any suitable means, as for instance, by any well known or suitable means (not shown) acting in response to radiant energy. The opposite ends of the solenoid 51 for controlling the propellers, are connected by wires 83 and 86 with the wires 76 and 81, respectively, thus connecting the solenoid 51 in parallel with the solenoid 75.

In the operation of the form of this invention just described, when it is desired to launch the torpedo 6 from the tube 5 the switch 79 is closed, as for instance in response to an impulse of radiant energy, or in some other manner, thus energizing the 90 solenoid 75 which will then draw the plunger 66 slowly inwardly against the action of the spring 69, and the retarding effect of the pipe 70 and valve 71, thus ultimately causing the movable contact 62 to engage the 95 fixed contact 65, closing the circuit through the battery 60 and solenoid 13 and thus causing the valve 11 to be moved into such a position as to permit compressed air from the source 9 to enter the inner end of the 100 torpedo tube 5 and to eject the torpedo 6 from the tube. But immediately upon the closing of the switch 79 and before the movable contact 62 has been moved into engagement with the stationary contact 65 to 105 cause the ejection of the torpedo, the solenoid 51 controlling the propellers will be energized and will draw the plunger 50 inwardly, thus moving the slide valve 47 into position to permit compressed air to enter from 110 the pipe 42 into the inner end of the cylinder 40, thus forcing the piston 39 outwardly and causing the levers 25 and 26 to push the sleeves 22 and 23 outwardly to diminish the 115 pitch of the propeller blades 18 and 19, and thus cause a decrease in the speed of the torpedo boat before the air has been admitted to the torpedo tube to eject the torpedo. The outward movement of the sleeves 22 and 23 may be limited so as to cause the propeller blades 18 and 19 to be oscillated into 120 neutral positions, or the sleeves 22 and 23 may be permitted to move outwardly under the action of the piston 39 to a sufficient extent to reverse the pitch and consequent 125 propelling effect of the propeller blades 18 and 19, and in the latter case the decrease in the rate of movement of the boat would be more marked. By a proper adjustment of 130 the valve 71, the action of the corresponding

piston 68 may be so timed as to permit the speed of the torpedo boat to be automatically decreased to any desired extent upon the closing of the switch 72 and before the 5 air has been admitted into the torpedo tube 5 to eject the torpedo 6.

When the switch 79 is opened, solenoid 75 is deenergized and the plunger 66 moved outwardly under the action of the spring 69, 10 and this moves the contact 62 quickly away from contact 65, thus deenergizing solenoid 13. The valve 11 is then closed under the action of the spring 14. At the same time that solenoid 75 is deenergized, solenoid 51 is also 15 deenergized, thus allowing valve 47 to assume the position shown in Fig. 1. The piston 39 is then moved slowly inwardly under the action of the spring 54, the rate of this motion being controlled by the valve 46. As 20 the piston 39 is moved inwardly, it will automatically increase the pitch of the propellers 18 and 19 so that the boat is gradually brought up to full speed ahead, or in other words, returned to its initial speed.

25 In the form of this invention shown in Fig. 2, the arrangement is such that the compressed air is first admitted into the torpedo tube and then acts to diminish the speed of the boat. In this form of the invention, a 30 torpedo tube 90 is secured in the torpedo boat in any suitable position to support a torpedo 91, and this tube is provided at its inner end with a pipe 92 controlled by a manually or otherwise operated valve 93, and 35 leading from a tank 94 or other source of compressed air. For controlling the speed of the boat, a pipe 95 leads from the inner end of the torpedo tube 90 into one end of a fixed cylinder 96 which contains a recipro- 40 catory piston 97 secured to one end of a piston rod 98, which carries at its outer end a contact 99 arranged to reciprocate into and out of engagement with a stationary elongated contact plate 100. The piston 97 is 45 normally held in an inoperative position by means of a compressed spring 101 arranged in the cylinder 96. For controlling the rate of movement of the piston 97, the outer end of the cylinder 96 communicates with the sur- 50 rounding air through a pipe 102 controlled by an outwardly opening check valve 103 and provided with a by-pass 104 controlled by an adjustable needle or globe valve 104', the construction and arrangement being such 55 that when the piston 97 moves outwardly the air is allowed to pass freely out of the outer end of the cylinder 96 through the check valve 102 and by-pass 104, but when the piston 97 moves inwardly the air is not 60 permitted to pass into the outer end of the cylinder 96 through the check valve 103 but only through the by-pass 104, and the inward movement of the piston 97 may thus be controlled or retarded to any desired extent. 65 The movable contact 99 is connected by a

coiled wire 105 with one end of a fixed electromagnet 106, the other end of which is connected by a wire 107 with one pole of a battery 108, the other pole of which is connected by a wire 109 with the fixed contact 70 plate 100. The electromagnet 106 is arranged to control a pivoted switch 110 which is arranged to cooperate with a stationary contact 111 to control a circuit 112 and 113, the switch 110 being normally held closed by a 75 spring 114, and the circuit 112, 113 being the ignition circuit or circuits of the driving means by the breaking of which one or more of the internal combustion driving engines is stopped. The circuit 112, 113 however, 80 may be arranged to control the speed of the boat in any other suitable manner.

In the operation of the modified form of this invention shown in Fig. 2, when it is desired to launch the torpedo, the valve 93 is 85 opened in any suitable manner, or by any suitable means, thus admitting air from the tank 94 into the inner end of the torpedo tube 90 where it initiates the launching movement of the torpedo 91, and simultaneously 90 presses the piston 97 quickly upwardly, thus closing the circuit through the battery 108 and electromagnet 106 to decrease the speed of the boat, and the construction arrangement may be such that a modification of the 95 action of the propelling means to decrease the speed of the boat will be effected at about the same time that the torpedo 91 issues from the tube 90 under the action of the compressed air in the tube. 100

After the torpedo has left the tube and the supply of air from the tank 94 has been shut off by closing the valve 93, the piston 97 will be moved inwardly by the spring 101, its rate of motion being controlled by 105 the adjustable valve 104', so that a certain predetermined length of time will elapse after the firing of the torpedo and before the circuit through the solenoid 106 will be broken by the contact 99 moving from the 110 contact 100. When the solenoid 106 is de-energized, the circuit is again completed through the wires 113 and 114, and the engines restarted by any suitable means and in 115 any suitable manner so as to return the boat to its initial speed.

In the modified form of this invention shown in Fig. 3, the construction may be the same as that hereinbefore described and shown in Fig. 2, except that instead of providing means for controlling the speed of the boat by breaking the ignition circuit as shown in Fig. 2, means are provided whereby the speed of the boat is decreased by changing the times of sparking in the cylinders of the internal combustion engines driving the propellers. In this modified form of the invention, the wires 105 and 107 of Fig. 2 instead of leading to the electromagnet 106, are arranged to lead to the opposite 120 125 130

ends of a solenoid 120 arranged to control a core 121 which forms one end of a rod 122 arranged to reciprocate in a fixed path and to oscillate arms 123 and 124 which are rigid 5 with rotatable sleeves 125 and 126 which control in a well known manner the times of 10 sparking in the cylinders of the gas engines, which in this form of the invention are arranged to rotate the propellers of the boat. 15 In this form of the invention a spiral spring 126 surrounding the core 121 and compressed between the solenoid 120 and a collar 127 rigid with the core 121, normally holds the rod 122 in such a position as to 20 cause the engines to operate at their maximum rate, and when the solenoid 120 is energized, as by closing the switch 99 in Fig. 2, the arms 123 and 124 will be swung clockwise to vary the times of sparking in the engines and thus decrease the speed of the engines, and consequently the speed of the 25 torpedo boat. When the solenoid 120 is de-energized by the opening of the switch 99, the arms 123 and 124 will be returned to their original position by the action of the 30 spring 126 so as to return the boat to its initial speed.

In the form of this invention shown in Fig. 4, the construction is such that the 35 speed of the boat is decreased by throttling the propelling engines simultaneously with the admission of air into the torpedo tube to eject the torpedo from the tube. In this form of the invention, the construction is 40 similar to that shown in Fig. 1 and hereinbefore described, comprising a torpedo tube 5 arranged to support a torpedo 6, and communicating through a pipe 7 with a source 9 of compressed air, the pipe 7 being controlled by a valve 10 and by a slide valve 11 arranged to be actuated as the result of the 45 energization of a solenoid 13, as hereinbefore described and shown in Fig. 1.

One end of the solenoid 13 is connected 50 through a wire 130 with one pole of a battery 131, the other pole of which is connected by a wire 132 with a fixed contact 133, which is arranged to be engaged by a pivoted switch 134 which is connected by wire 135 with the other end of the solenoid 13, the switch 134 being normally held open by a spring 135' and being arranged to be closed in any suitable manner, as for instance, by the closing of a circuit through a 55 fixed electromagnet 136. The wires 130 and 135 are connected by wires 137 and 138 to the opposite ends of a solenoid 139, which is arranged to reciprocate a piston rod 140 one end of which forms a core for the solenoid 60 139, and the other end of which is provided with a piston 141 arranged to reciprocate in a fixed cylinder 142, the piston 141 being normally held in its outermost position in the cylinder 142 by a spiral spring 65 143.

For controlling the outward movement of the piston 141, the inner or right hand end of the cylinder 142 communicates with the surrounding air through a pipe 144 controlled by an outwardly opening check valve 145 70 and provided with a by-pass 146 controlled by an adjustable needle or globe valve 147, the construction and arrangement being such that when the piston 141 moves outwardly or towards the right the air passes freely 75 out of the right hand end of the cylinder through the check valve 145 and by-pass 146, but when the piston 141 moves towards the left the air is allowed to pass into the right hand end of the cylinder only through the 80 by-pass 146, and the rate of movement of the piston 141 under the action of the spring 143 may therefore be regulated or controlled by a suitable adjustment of the needle or globe valve 147. The outer or left hand end 85 of the cylinder 141 is provided with open ports 147' to permit free movement of the air into and out of the left hand end of the cylinder.

The piston rod 140 is provided with two 90 pins 146' and 147' fixed thereon, which engage slidably in slots 148 and 149 in levers 150 and 151 which are rigid with stems 152 and 153 which are arranged to control the throttles of the engines for actuating the 95 propellers 16 and 17 of the boat. The stems 152 and 153 might be arranged to control not only the throttle valves of the engines, but also the spark system as hereinbefore 100 described.

In the operation of this modified form of the invention shown in Fig. 4, when the switch 134 is closed as in response to an impulse of radiant energy or in any other suitable manner, the two solenoids 13 and 139 will be simultaneously energized to open 105 the slide valve 11, and thus admit compressed air into the tube 5 to expel the torpedo 6, and to simultaneously move the rod 140 towards the right, the valve 145 allowing free passage of air when piston is moved to the right to reduce the speed of the engines and consequently the speed of the boat.

When the solenoid 136 is deenergized the 115 switch 134 is opened under the action of the spring 135' thus deenergizing solenoids 13 and 139, the former allowing the valve 11 to be closed while the latter allows the rod 140 to be moved to the left under the action of 120 the spring 143, the rate of motion of the piston 141 being determined by the setting of the valve 147 so that the boat is gradually brought up to the speed in a predetermined length of time.

In the form of this invention shown in Fig. 5, the construction and arrangement is similar to that hereinbefore described and shown in Fig. 2, except that instead of providing means for ejecting the torpedo by 125

- compressed air, means are provided for ejecting the torpedo as the result of the explosion of suitable explosive material arranged in the torpedo tube. In this form of the invention, the torpedo tube 160 for holding the torpedo 6 is provided with a rounded or approximately semi-spherical end 161 in which is arranged a suitable explosive material or mixture of material 162 and a fuse 163 for exploding the same, the fuse being arranged to be rendered effective by means of an electric circuit 164 leading through a battery 165 and a normally open pivoted switch or other suitable switch 166. The torpedo tube 160 is provided as hereinbefore described in connection with Fig. 2, with an outlet pipe 95 and other cooperating parts 96, etc. for energizing an electromagnet 106 to open a normally closed circuit 112, 113.
- In the operation of the form of the invention shown in Fig. 5, when the switch 166 is closed, the explosive material 162 is exploded, thus generating a high gaseous pressure at the inner end of the torpedo to eject the torpedo from the tube 160, and this gaseous pressure simultaneously passes through the pipe 95 and forces the piston 97 outwardly to close the circuit through the electromagnet 106 and to break the ignition circuit 112, 113 of the propelling engine or engines. A predetermined time after the torpedo 6 has been thus ejected from the tube 160, the electromagnet 106 is deenergized by the movement of the movable contact 99 from the contact plate 100 thus permitting the closing of the ignition circuit 112, 113, which will cause the propelling engine or engines to return to their initial speed as hereinbefore described.
- In the form of this invention shown in Fig. 6, the torpedo tube 160 for holding the torpedo 6 is provided with a rounded end 161 containing a suitable explosive material or mixture of materials 162 arranged to be exploded by the fuse 163 controlled by a circuit 170, including a battery 171, a movable contact 172 and fixed contact plate 173. The movable contact 172 is carried on a rod 174 to which is attached a piston 175. This piston moves in a cylinder 176 under the action of a spring 177, the rate of motion being controlled by the valve mechanism 178 which is similar to that used in Fig. 1 in connection with cylinder 67. The movable contact 172 is normally out of engagement with the fixed contact plate 173 by a trip 179, which forms the core of a solenoid 180 and which is held in engagement by a spring 181. The solenoid 180 is controlled by a circuit 164, including a battery 165 and normally open switch 166 as hereinbefore described, and the circuit 164 is connected by wires 167 and 168 with the opposite ends of a solenoid 169, thus connecting the solenoid in parallel with the solenoid 180 and causing the solenoid 169 to be energized when the solenoid 180 is energized by the closing of the switch 166. This solenoid 169 may be arranged to control the speed of the boat in any suitable manner. For instance, this solenoid 169 may be arranged to act in a manner similar to that of the action of the solenoid 51 shown in Fig. 1 to cooperate with the parts there shown for changing the pitch of the propellers 16 and 17, or the solenoid 169 might be arranged to act in a manner similar to that of the action of the solenoid 139 shown in Fig. 4 to cooperate with the parts there shown for controlling the throttles of the propelling engines and thus cooperate with the torpedo launching means to control the speed of the boat, as hereinbefore described.
- Although only a few of the many forms in which this invention may be embodied have been shown and described herein, it is to be understood that the invention is not limited to any specific construction but might be embodied in various forms without departing from the spirit of the invention or the scope of the appended claims.
- Having thus fully described this invention, I claim:
1. The combination with a movable body of propelling means therefor, means for launching a projectile from said body, and co-operating means for controlling said propelling means and the said launching means.
  2. The combination with a movable body, of propelling means therefor, means for launching a projectile from said body, means operative to modify the action of said propelling means, and means controlled by the said modifying means for causing the actuation of said launching means.
  3. The combination with a movable body of propelling means therefor, means for launching a projectile from said body, means operative to modify the action of said propelling means, and means cooperating with the said modifying means for causing the actuation of said launching means.
  4. The combination with a movable body of propelling means therefor, means for launching a projectile from said body, and means automatically operative for successively modifying the action of said propelling means and initiating the action of said launching means.
  5. The combination with a movable body of propelling means therefor, fluid pressure means for launching a projectile from said body, means for modifying the action of said propelling means, and means controlled by said modifying means for controlling said fluid pressure launching means.
  6. The combination with a movable body, of means including a propeller for actuating said body, means for discharging a projectile from said body, and means cooperating

with said discharging means for varying the speed of said body by changing the pitch of said propeller.

7. The combination with a movable body, of propelling means therefor, means for launching a projectile from said body, and means cooperating with said launching means for automatically controlling the action of said propelling means so as to decrease and then to increase the speed of said body.

8. The combination with a movable body, of a support carried thereby for holding a projectile, means for discharging a projectile from said support while said body is in motion at a given rate, and means operatively connected to said discharging means for modifying said rate.

9. The combination with a movable body, of a support carried thereby for holding a projectile, means for discharging a projectile from said support while said body is in motion at a given rate, and means operatively connected to said discharging means for reducing said rate.

10. The combination with a movable body, of a support carried thereby for holding a projectile, means for discharging a projectile from said support while said body is in

motion at a given rate, and means controlled by said discharging means for modifying said rate.

11. The combination with a movable body, of a support carried thereby for holding a projectile, means for discharging a projectile from said support while said body is in motion at a given rate, and means controlled by said discharging means for reducing said rate.

12. The combination with a movable body, of a support carried thereby for holding a projectile, means for discharging a projectile from said support while said body is moving, and means controlled by said discharging means and automatically operative first to reduce and then to increase the rate of movement of said body.

13. The combination with a movable body, of means including a propeller having a reversible pitch, means carried by said body for discharging a projectile therefrom, and means controlled by said discharging means for reversing the said pitch.

Signed at Gloucester, in the county of Essex and State of Massachusetts this 4th day of January, A. D. 1916.

JOHN HAYS HAMMOND, JR.
